ADJUSTABLE-BED CASKET

George C. Hillenbrand and William H. McCullough, Batesville, Ind., assignors to The Batesville Casket Company, Batesville, Ind., a corporation of Indiana

Application March 22, 1950, Serial No. 151,174

10 Claims. (Cl. 27—12)

1

This invention relates to a new and improved casket in which the casket bed may be tilted from side to side or end to end as well as raised and lowered.

Heretofore only a limited degree of bed adjustability has been provided in caskets. Current commercial models may have a plurality of spaced wall brackets along the sides of the casket which engage springs or other bed support means. The springs can thus be moved up or down prior to insertion of the mattress. Other structure has been proposed to provide tilting in which the bed support lies along one side length of the casket floor. Beneath it is a frame which has adjustable lugs on the opposite side of the casket floor by which this side of the bed support may be raised relative to the other. It will be noted that each of these structures provides a substantial area of abutment with the casket floor or walls, that neither alone provides both elevation and tilting, and that individually their adjustability is less than optimum. These devices are cumbersome and lack flexibility since the adjustments are made in steps rather than being continuously adjustable from maximum to minimum. In this described tilting the choice lies simply between tilt and no-tilt, and the specific angle of tilt is fixed by the length of the particular lugs.

The present inventors, on the other hand, here provide a bed adjustment completely flexible over a wide range of levels and angles. In caskets of this invention the mattress may be positioned from extremes in which the top is substantially flush with the top rim of the body of the casket to a level at which the mattress abuts the casket floor. Similarly, the mattress may be canted from side to side or sloped from end to end or even twisted, if desired, over a range limited only by the dimensions of the adjusting mechanism. Of equal significance are the facts that the adjustment as to both level and cant may be made gradually over the entire possible range and that the adjustments can be made just as easily with the corpse and mattress in position as when the springs or bed support alone are in the casket.

One of the accomplishments of this invention has been to locate the casket bed positioning mechanism in an otherwise unused portion of the casket shell in order that the overall appearances of both the casket interior and exterior are not adversely affected; that is, the adjusting mechanisms are completely hidden from view, nestled in opposed end recesses of the casket shell. This structure also permits the actuating

2

openings for the mechanism to be readily accessible to the funeral director up to the final moment of closing and sealing the casket without marring the appearance of the casket by such access openings.

In order to provide a casket bed which can be adjusted over the entire range between the extremes of top and bottom, it is obvious that no bulky positioning mechanism can occupy a central position of the casket floor; otherwise the bed could not be lowered to the fullest possible extent. This fact, together with the requirements of unobtrusiveness, mentioned earlier, makes it evident that some means must be provided for distributing the load of the mattress and the corpse throughout the casket shell as it cannot be done by spaced bed support members abutting the whole area casket floor. On the other hand, there is every reason to believe that the concentration of such a load at the extremes of a sheet metal casket floor would result in distortion of the casket shell at the points of load sustenance or might even result in buckling or even penetration through the floor itself. Obviously, some means must be found to dissipate the effect of concentrating in a small area an entire load in a structure which heretofore has borne similar loads by a plurality of spaced abutment contacts. Thus, it is one concept of our invention to employ, in sheet metal caskets, rigidifying or reinforcing construction of the casket floor cooperating with the floor-abutting, load-sustaining members of the actuating apparatus in order to effectively distribute the load over the entire shell.

For one reason or another, it may be desirable to adjust the upper part of the corpse at one particular side-to-side cant, or angle, and to leave the legs either in a straight level position or at some other angle; therefore, it is particularly advantageous to provide a structure in which the degree of cant may vary throughout the length of the casket. Further, the canting of the casket bed by independent manipulation of its foot and head ends also inherently involves twisting, or warping, the casket bed. For whatever reason warpage is deemed desirable or necessary, this invention provides structure, including flexible springs or other flexible support means, to permit such warpage over a wide range. Through gravity, the load of the mattress and corpse then accommodate themselves to the exact spring configuration which has been produced by actuation of the tilting mechanism.

Nonetheless, the use of such a flexible support has been found to create additional problems,

especially when, for reasons already mentioned, it has been found desirable to leave the middle portion of the casket bed unsupported relative to the floor. A corpse weighing, for example, two hundred pounds results in tremendous forces pulling down and toward the center of the casket when it is laid on a flexible, yielding bed. The sagging produced by such a load transmits this pull to the positioning mechanisms at the respective ends of the casket. One embodiment of this invention therefore incorporates in the positioning apparatus itself structure which is best adapted to resist the tendency of the load of the corpse and mattress to pull them away from the casket ends. Additionally, the apparatus is journalled in bearings carried by the casket end walls.

In addition to the fact that adjustments of the casket level can be made without tearing the bed apart, caskets constructed in accordance with our invention make it possible as a practical matter for the funeral director to carry out the positioning of the corpse in the presence of the deceased's relatives. Heretofore, the inaccessibility of the positioning apparatus after the body is put into the casket had limited the changes to such arranging as manipulation of the corpse itself and adjustments of the pillow and padding in the casket. Naturally, no funeral director likes to move the corpse about in the presence of relatives of the deceased, so the only recourse has been to ask them to leave the room while some rearrangement is made in the exact location of the corpse in the casket, and then their approval is solicited after the change has been made. It will be appreciated that this procedure has been less than satisfactory to everyone involved since any particular shift has little chance of meeting the approval of even one relative and certainly not the concurrence of several. Caskets embodying our invention, on the other hand, provide universal flexibility of the bed so that, by adjustments made without touching the corpse, its exact position in the casket can be moved about and arranged with the benefit of mutual suggestions and criticisms of everyone present until the effect is that desired by all concerned.

In addition to the chance for the funeral director to obtain, in adjusting the corpse within the casket, the active assistance of those most concerned with its appearance, caskets of this invention find utility from the funeral director's point of view at an earlier stage in the preparation of the body for the services.

In current commercial model caskets, bed-adjusting mechanism is either entirely lacking or so inadequate that virtually all shifts and alterations involve the funeral director's lifting and repositioning of the bed or corpse or both. Adjustable-bed caskets of this invention reduce the physical exertion on the part of the director to a minimum. An additional factor which reduces the over-all strain on the director is that all of the adjustments with the exception of the actual lifting of the corpse into the casket can be made by one person alone, an advantage not heretofore attainable. Even in the step of getting the corpse into the casket, this invention makes an improvement possible. Heretofore when the corpse is put into the casket, the problem had been one of lifting it up and over the side wall into the trough in which the mattress lies; in caskets of this invention, the raising of the bed and mattress to the level of the top rim of the casket shell makes it only necessary to place the corpse

on the shelf thus formed. After putting the corpse in the casket in this fashion, the mattress and corpse may then be lowered by actuating the adjusting apparatuses at the respective ends of the caskets.

The very fact that changes in the arrangement of the corpse can be made more easily than before helps insure that a more than satisfactory presentation can be made at the time the relatives are first called in to view the body. That is, the exact desired position of the bed and corpse for display when the casket is open need not represent a guess on the mortician's part in which the position of the bed must be determined before the corpse is laid in the casket. Rather, all the meticulous adjustments can be made with full knowledge of exactly how the results will look.

Other advantages and objects of the invention will be apparent from the accompanying drawings and description thereof. For clarity's sake, in Figures 1-10 and 12 the structure is shown prior to insertion of the conventional mattress and fabric lining for the casket body, it being understood that the mattress should be dimensioned to avoid binding against the casket walls so that it will ride up and down and tilt in response to the corresponding movement of the springs or other support on which it rests. Figures 1 through 10 represent one embodiment of the invention; Figures 11 and 12 show a preferred modification.

In the figures:

Figure 1 is a plan view of a casket from above, broken in the middle in order to provide an enlargement of the casket bed positioners at the respective ends thereof, showing springs carried by these respective adjusting mechanisms.

Figure 2 is a section taken along line 2-2 of Figure 1, showing the casket bed in a level position.

Figure 3 is an enlarged view of one of the ends shown in Figure 2.

Figure 4 is a section taken along line 4-4 of Figure 3.

Figure 5 is a view similar to Figure 4 in which the tilting mechanism has been actuated and the casket bed is therefore canted.

Figure 6 is an enlargement of a portion of the casket shown in Figure 1 showing additionally a plaque with tilting and lift indicia indicated thereon.

Figure 7 is a sectional view taken along line 1-1 of Figure 4.

Figure 8 is a diagrammatic view of a casket body in which the respective positioning mechanisms have been adjusted to provide a sloping from head to foot.

Figure 9 is a diagrammatic view of a casket body in which the respective tilting mechanisms have provided a back to front cant of the casket bed.

Figure 10 is a diagrammatic view showing a combination of the effects of Figures 8 and 9 in which the casket bed not only slopes from head to foot, but also is canted from back to front.

Figure 11 is a section of a casket taken from the side, showing the preferred embodiment. Springs and mattress are indicated in place at an intermediate level; dot-dash lines show them at two other levels.

Figure 12 is a section taken along line 12-12 of Figure 11.

The disclosure in the drawings and in the following description is made with specific respect

to sheet metal caskets, in which there is a special need for the aforementioned rigidifying structure. Alternatively, the adjusting bed mechanism can be employed in caskets made of other materials, such heavier metal construction than customary or wood or plastic, which may inherently have durable qualities which do not require a reinforced floor in conjunction with the mechanism.

The casket structure shown includes journals for the casket bed at its respective ends for pivotal movement of the bed and the resultant tilting; additionally, it includes means for raising and lowering the level of the bed itself. Specifically, changes in casket bed levels are attained by a screw and nut elevator mechanism, located at either end, or both ends, of the casket. The pivot points are arranged to ride up and down coincident with movements of the nut along the elevating screw shaft, so that a tilt can be obtained at any bed level, independently of the elevator mechanism. In order that the tilt of the bed produced by its pivotal movement can be fixed at any degree, means are provided to hold the bed in any of the plurality of pivoted positions. In the structure shown, these means generally comprise a rack meshed with a worm, both of which ride up and down along with the nut of the elevator mechanism. The rack is mounted to allow pivoting relative to the nut. Thus, the teeth of the rack engage the worm and hold the bed at a specific angle.

A casket embodying this invention has a shell, generally designated as 10, which has sides 11, 11, ends 12, 12 and a floor 13. An inturned flange 14 extends continuously about the top rim of the body 10. At the middle of each of the part of flange 14 adjacent ends 12 is an end-wall flange extension 15 which serves incidentally as a plaque to distinguish the "tilt" means from the "lift" means. An elevating screw 18 is secured in the plaque 15 at bearing 15a and depends into the casket body proper. At its base it is secured by cup 19 against lateral displacement but is free for rotation. Threaded shaft 18 has an operative head 21, shown socketed to afford a recess for receiving a corresponding key, not shown, rotation of which produces corresponding rotation of screw 18. A solid hexagonal shaft 23 is disposed parallel to screw 18 and is similarly journalled in plaque 15 from which it depends into the casket body. For simplicity of operation, shaft 23 is also machined to provide an operative head for receiving a key of similar configuration to that which will rotate screw 18. The tip of shaft 23 resides in a cup 24 similar to aforementioned cup 19. Cups 19 and 24 are carried by a frame 20, which abuts floor 13 at its transverse rib 16 and along the lower-level rib 17. Ribs 16 and 17 in fact extend about the entire perimeter of the casket floor. Rib 16 is spaced from the marginal exterior to provide a convenient hand-hold and to strengthen the casket floor, but more importantly the rib structure distributes the thrust of the load of the corpse, transmitted through shafts 18 and 23, throughout the area of the floor 13.

The casket body 10 is designed to accommodate a mattress spaced above the floor 13. Such a mattress is supported by springs, generally designated by 25, which include end angle irons 26 and side angle irons 27. As shown, each end of springs 25 is supported by a pair of brackets 28 which are in turn integral with, and extend from, the upper part of an inner plate 29 having arcu-

ate slots 30 and 31 and a peripheral set of teeth in the rack 32. Thus, the levels of the respective pairs of brackets 28 determine the levels of the ends of the springs carried thereby. For example, as the brackets at the head end of the casket are raised relative to the foot end, the ends of brackets 28 at one end of the casket become farther away from the corresponding parts of brackets 28 at the other end. In the absence of stretchable springs, some means must be provided to accommodate these variations in spacing between corresponding parts. This is accomplished by having bolts 29a, which otherwise secure springs 25 against lateral displacement relative to brackets 28, freely slide in slots 28a toward, and away from, the casket end walls. The conventional nuts and washers employed with bolts 29a are suitably spaced to permit the free play necessary for this sliding of the bolts relative to brackets 28.

Plate 29 is pivotally attached by a rivet 33 to outer plate 34 which in turn has tabs or nuts 35 and 36, each of which have a screw threaded aperture, forming a skeletal nut which receives elevating screw 18. Additional, outer plate 34 is apertured at 41 and 42 to receive guide pins 38 and 39 riding in slots 30 and 31, respectively, of adjacent plate 29. Thus, plate 29 is free to swivel relative to plate 34, but it cannot pivot beyond the limits defined by the engagement of the pins 38 and 39 with the extremes of slots 30 and 31. The teeth of rack 32 are an arc of a circle whose center is pivot pin 33. Element 34 has a yoke 43 which carries a worm 45 meshing with the teeth of rack 32. Gear 45 has a bore therethrough which slidably accommodates shaft 23, and this bore is, at least in part, dimensioned to be driven upon rotation of shaft 23. As shown, this is accomplished by making this bore 46 of hexagonal cross section through which shaft 23, also hexagonal in cross section, fits snugly, but with sufficient clearance to avoid binding on up and down movement. Any other splinelike arrangement, as will readily be apparent to those skilled in the art, would be suitable for this purpose, as long as worm 45 is free to ride up and down shaft 23 upon elevation or lowering of plate 34. This up and down movement of plate 34, of course, occurs in response to rotation of elevating screw 18.

The heads of guide pins 38 and 39, together with the engagement of worm 45 and rack 32, provide bearings for dissipating throughout plate 34 the effect of a load placed on yieldable springs 25.

As shown, the nuts 35 and 36 of element 34 are spaced from gear 45. For stability consistent with simplicity of structure, two spaced nuts (comprising a skeletal nut) are provided, but it will be appreciated that a single nut could satisfy the desired function. Shafts 18 and 23 are shown parallel; therefore, the nut or nuts which ride up and down screw 18 lie in a plane substantially parallel to that of threads of gear 45. Upon the tilting of the casket bed support which is produced upon rotation of shaft 23 and consequent rotation of gear 45, that portion of the casket bed which lies adjacent to elevating screw 18 will remain at the same level while the sides of the casket bed will be relatively lowered or raised with respect to this fixed level. At any desired cant of the casket bed the entire supporting assembly may be elevated or depressed upon rotation of screw 18, which causes member

34, including the gear 45, to ride up or down screw 18 and relative to shaft 23.

Figures 8, 9 and 10 demonstrate three types of the positions which may be attained through adjustments of the respective shafts.

A strip of cloth 47 is shown employed to keep elevating screw 18 from soiling lining and other trappings of the casket, which are added subsequently. Strip 47 is attached beneath plaque 15 to block 48 and is held taut by a coil spring 49 hooked in tab 50 of frame 20. Plate 29 is slotted at 51 to accommodate covering 47.

In the preferred embodiment shown in Figures 11 and 12, it will be noted that casket bed support braces 52 extend from the lower margin of pivot plate 54 which in other respects is substantially identical to plate 29 of the embodiment shown in Figures 1 through 7. A chief advantage of the structure of Figures 11 and 12 is that the bed support and mattress occupy a level adjacent that of the plate structure of the positioning mechanisms and may therefore be lowered all the way to the floor. In this way there is no wasted space at the bottom of the casket which otherwise occurs when the bed support brackets are extensions of the upper margin as in pivot plate 29.

In Figure 11, mattress 56 rests on springs 25. In the uppermost position of springs 25 and mattress 56 of this figure, shown in dot-dash lines, addition of decorative cloth trappings to hide mattress 56 raises the effective level of the bed to substantially that of flange 14.

Thus, it will be seen that caskets embodying this invention represent an improvement in the mechanics of displaying a corpse at and before the funeral services. This improvement is directly reflected in the saving of time of the funeral director, in the saving of his physical efforts, and in a more satisfactory showing of the corpse at the time of display.

Having described our invention, we claim:

1. Mechanism for adjusting the bed of a casket comprising a nut and a cored worm maintained in fixed spacial relationship with each other, an elevating screw engaging said nut, a rotatable shaft disposed through the core of said worm and cooperating therewith to drive said worm upon rotation thereof, said worm slidable relative to said shaft, a casket bed support pivotally secured to said nut for up and down translation therewith, and an arcuate rack associated with said support in fixed spacial relationship to said nut and meshed with said worm whereby rotation of said shaft angulates said casket bed support.

2. In a casket the combination of a casket bed, a swivel plate secured to an end of said bed, support means for pivotally carrying said swivel plate, an arcuate rack mounted at the periphery of said swivel plate, a worm having a bore, said worm meshed with said rack, a vertical shaft journalled in the end of said casket, said shaft disposed through said worm for guiding said worm during vertical movement thereof, said shaft being dimensioned to drive said worm upon rotation of said shaft whereby said bed is tilted from side to side, and means for moving said worm up and down relative the floor of the casket so that said bed may be tilted with said swivel plate disposed at any height above the floor of said casket.

3. An adjustable-bed casket comprising a casket shell, means reinforcing the floor of said shell, a casket bed, a swivel plate secured to said casket bed, gear teeth mounted at the periphery

of said swivel plate, a bearing plate pivoted to said swivel plate, a worm carried by said bearing plate and meshed with said gear teeth, an elevating screw secured in said casket shell and journalled in said bearing plate for raising and lowering said casket bed, a drive shaft journalled in said worm, said drive shaft and said screw abutting the floor of said casket shell whereby said reinforcing means tends to distribute the effective weight of a load upon said casket bed throughout said casket shell floor.

4. In combination with a casket, an adjustable bed and means for adjusting said bed comprising: an elevating screw journalled in one end of the casket, two plates secured together in flush relationship, the inner of said plates secured to said bed, the outer of said plates screw-threaded and riding up and down said elevating screw, a worm carried by said outer plate, gear teeth mounted on the inner of said plates and meshed with said worm, and means for driving said worm, the inner of said plates translatable up and down in conjunction with the outer of said plates but mounted for pivotal movement relative thereto, each of said plates bearing against the other when a load is placed upon said bed.

5. In a casket the combination of a flexible bed, a swivel plate secured to one end of said bed, an outer bearing plate mounted flushwise adjacent said swivel plate and away from said bed, said swivel plate secured to said outer bearing plate at a pivot point for pivotal movement relative thereto, a rack at the periphery of said swivel plate, a worm meshed with said rack and carried by said outer bearing plate, an elevating screw journalled in the shell of the casket and carrying said outer bearing plate up and down upon rotation thereof, and means for rotating said worm to cant said flexible bed.

6. In a casket, the combination of a flexible bed, a swivel plate secured to each of the respective ends of said bed, outer bearing plates mounted flushwise adjacent said swivel plates and away from said bed, each of said swivel plates secured to its corresponding bearing plate at pivot points for pivotal movement relative thereto, an arc of gear teeth mounted on each of said swivel plates radially with respect to said pivot points, a worm meshed with each of said gear teeth and carried by each of said outer bearing plates, an elevating screw journalled at each end of the shell of the casket and carrying said outer bearing plates up and down upon rotation of said screws, and means for rotating said worms to cant said flexible bed.

7. A casket having an adjustable bed, said casket comprising a casket body; an adjusting mechanism secured to each of the opposed ends of said body; each of said mechanisms including: a pair of plates secured together for relative pivotal movement, one of said plates carrying a casket bed support and a rack, the other of said plates carrying a worm meshed with said rack and screw-threaded to receive a vertical screw, a screw journalled in said worm-carrying plate disposed vertically alongside an end of said casket body and abutting the floor of said casket body, and means for driving said worm; and a bed riding on said bed supports.

8. In a casket, a first shaft and a second shaft, said shafts rotatably journalled within an end of said casket, each of said shafts having an exposed operative head by which the shaft may be rotated, a flexible bed disposed within said casket,

elevating nut means in screw threaded engagement with said first shaft, pivotable bed support means securing an end of said bed to said elevating nut means, and bed tilting means for effecting relative rotative movement between said elevating nut means and said pivotable bed support means, said bed tilting means being slidably and operatively associated with said second shaft.

9. In a casket, the combination of a casket bed, a swivel plate secured to an end of said bed, support means pivotally journaling said swivel plate upon an axis of rotation extending longitudinally of said casket, a gear rack on said swivel plate, said gear rack disposed upon an arc centered at the pivotal journal between said swivel plate and said support means, a worm having a bore, said worm being rotatably journalled in fixed relationship relative to said support means and meshed with said rack, and a shaft journalled in the end of said casket, said shaft slidably disposed through the bore in said worm and dimensioned to drive said worm upon rotation of said shaft whereby said swivel plate and bed may be tilted from side to side about said pivotal journal.

10. In a casket, a flexible bed, a vertically disposed elevating screw rotatably mounted within

the casket adjacent an end of said bed, elevating nut means threadedly engaging said elevating screw and adapted to ride said screw vertically upon rotation thereof, bed support means pivotally securing said end of the bed to said elevating nut means for tilting movement about an axis extending longitudinally of said casket, an arcuate rack disposed in fixed relationship to said bed support means, a worm rotatably mounted in fixed relationship relative to said elevating nut means and meshing with said rack, and means for rotating said worm whereby said end of the flexible bed may be twisted relative to the other end about said axis.

GEORGE C. HILLENBRAND.
